United States Patent Office

Des. 183,718
Patented Oct. 21, 1958

183,718

EXPANDED METAL SHEET OR SIMILAR ARTICLE

Dallas S. Casley, Belpre, Ohio, assignor to Penn Metal Company, Inc., Boston, Mass., a corporation of Delaware

Application December 16, 1957, Serial No. 48,913

Term of patent 14 years

(Cl. D54—2)

FIG. 1

FIG. 2

Fig. 1 is a top plan view of a complete repeat unit of my new design for an expanded metal sheet; and

Fig. 2 is an end view looking from left to right at Fig. 1.

I claim:

The ornamental design for an expanded metal sheet or similar article, substantially as shown.
